UNITED STATES PATENT OFFICE

2,185,456

LEG GUARD

Ralph H. Cheney, Des Moines, Iowa

Application July 1, 1938, Serial No. 216,989

3 Claims. (Cl. 36—2)

The principal object of my invention is to provide a shield for the back and sides of each of the legs of the user for preventing the legs or clothing surrounding the legs from becoming soiled by mud, rain or like.

Another object of my invention is to provide a leg shield which protects the legs and rear upper portion of the shoes of the wearer from receiving rain or like from the bottom of a raincoat or like garment.

A still further object of this invention is to provide a leg guard or shield that may be easily and quickly placed on or removed from the leg of the user.

A still further object of my invention is to provide a leg guard or shield that may be successfully worn without wrinkling or damaging the front crease of a pair of trousers.

A still further object of my invention is to provide a leg or guard shield that may be easily and quickly adjusted to fit various sizes and lengths of legs.

A still further object of my invention is to provide a leg shield that is economical in manufacture, durable in use and refined in appearance.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawing, in which:

Fig. 1 is a side view of my leg guard in use.

Fig. 2 is a longitudinal sectional view of the upper portion of my leg shield.

Fig. 3 is a bottom view of a portion of the adjusting means used in my leg shield.

Fig. 4 is a cross sectional view of my device taken on line 4—4 of Fig. 1.

Fig. 5 is a top plan view of the spring clamp used to support the upper end of the body portion of the shield to the leg of the user with a tie cord securing its two ends.

Fig. 6 is a side view of the spring clamp used in the device.

On rainy days, it is almost impossible to keep the back and sides of the legs or the garments surrounding the legs from becoming soiled with water and/or dirt. Mud and water are splashed upwardly on the backs of the legs or the garments or hose surrounding the legs, by the action of the feet walking over and on sloppy and dirty surfaces. Also, if a raincoat or like is used, water will run down the back of the raincoat and onto

the backs of the legs of the user. In many instances, the water will run down the rear back end portion of the shoes and into the shoes. I have overcome such objections by providing a quickly attachable and detachable leg shield that not only protects the back and sides of the leg but also extends down to a point below the upper rear end portion of the shoe.

Referring to the drawing, I have used the numeral 10 to designate the leg portion of a pair of trousers embracing a leg. The numeral 11 designates a shoe on the foot of the leg encased by the trouser leg. The numeral 12 designates the body portion of my shield made of any suitable moisture or water-proof sheet material and preferably of a flexible material. This portion 12 is designed to extend down the back and sides of the leg as shown in Fig. 1. The numerals 13, 14, and 15 designate horizontally extending tunnel loops formed in the upper portion of the member 12. These tunnel loops are formed by inwardly lapping the upper end portion of the member 12 and sewing as shown in Fig. 2. The stitching for forming these tunnel loops is designated by the numeral 16. These three tunnel loops are positioned one above the other as shown in Fig. 2. The numeral 17 designates a spring clamp substantially U-shaped as shown in Fig. 5 and capable of being selectively inserted through any one of the tunnel loops 13, 14 and 15. In Fig. 1, this spring clamp 17 is inserted through the tunnel loop 13. This spring clamp 17 frictionally engages the leg of the user directly below the knee and obviously holds and supports the upper portion of the member 12 on the leg as illustrated. If the user of the device has comparatively short legs the spring clamp 17 will be inserted through either the loop 14 or loop 15. If the clamp 17 is inserted through the loop 14 or loop 15, that portion of the member 12 that is above the selected loop may be folded inside the portion 12, thereby providing a neat appearing upper portion of my device. The outer end portions of the clamp 17 which frictionally engages the leg, has its two outer ends curved forwardly and outwardly to aid in guiding the device on the leg of the user. The two outer ends of the member 17 protrude beyond the portion 12 and each of these end portions has a hole 18. If desired, a string or lace 19 may extend from each of these holes 18 and be tied as shown in Fig. 5 to aid in further securing the upper end portion of the device to the leg of the user. The numeral 20 designates a horizontal band on the lower end portion of the member 12. The num-

eral 21 designates a plurality of spur buttons on this member 20 as shown in Fig. 4. These spur buttons 21 are located on the outer side of the device to facilitate their operation. The 5 numeral 22 designates a band secured to the inner lower end portion of the member 12 at one of its ends and having a button hole slot 23 in its other end portion. This member 22 is designed to extend downwardly under the 10 shoe of the user, directly in back of the heel of a shoe and then upwardly where its slot 23 is capable of selectively engaging any one of the spur buttons 21. The numeral 24 designates a band secured to the inner lower portion 15 of the member 12 at one of its ends and designed to extend around the front portion of the shoe and then rearwardly to permit its button slot opening 25 to selectively engage any one of the spur buttons 21. Obviously, these two members 20 22 and 24 when fastened will successfully hold the lower portion of the member 12 downwardly and forwardly on the foot. By providing a plurality of spur buttons 21, this portion of the device may be quickly and easily adjusted to 25 different sizes of feet and shoes. The length of the member 12 is such that its lower end portion will extend below and overlap the upper rear end of the shoe 11 as shown in Fig. 1. As the member 12 and the clamp 17 only engages the back and sides of the leg, the leg of the trousers may extend forward of these members as shown in Fig. 1 and the front crease of the trouser leg will, therefore, not be crumpled nor wrinkled nor distorted when my device is worn.

30 35 From the foregoing it will readily be seen that

I have provided a highly desirable leg shield that not only protects the back and sides of the leg, but prevents water from running into the rear open top portion of the shoe.

Some changes may be made in the construction and arrangement of my improved leg shield without departing from the real spirit and purpose of my invention, and it is my intention to cover by my claims any modified forms of structure or use of mechanical equivalents which may be reasonably included within their scope. 5

I claim:

1. In a device of the class described, a shield designed to embrace the rear portion of a leg, a tunnel loop formed in the upper portion of said shield, a U-shaped clamp extending through said loop having holes in each of its ends, and a string extending from the holes in said U-shaped member. 15
2. In a device of the class described, a shield designed to embrace the rear portion of a leg, a tunnel loop formed in the upper portion of said shield, a U-shaped clamp extending through said loop having holes in its ends, and means secured through said holes in said clamp for connecting the ends of said clamp and embracing the forward portion of the leg at times. 20
3. In a device of the class described, a shield designed to embrace the rear portion of a leg, a plurality of adjacent tunnel loops formed adjacent the upper portion of said shield, and a U-shaped clamp capable of selectively extending through any one of said tunnel loops. 25 30
